UNITED STATES PATENT OFFICE.

FREDERICK WATERHOUSE, OF WALLINGFORD, CONNECTICUT, ASSIGNOR
TO THE RACINE SILVER PLATE COMPANY, OF RACINE, WISCONSIN.

DESIGN FOR A SPOON OR FORK HANDLE.

SPECIFICATION forming part of Design No. 12,840, dated March 28, 1882.

Application filed February 13, 1882. Term of patent 3½ years.

To all whom it may concern:

Be it known that I, FRED. WATERHOUSE, of Wallingford, in the county of New Haven and State of Connecticut, have invented a new 5 Design for Spoon or Fork Handles; and I do hereby declare the following, when taken in connection with accompanying drawing and the letters of reference marked thereon, to be a full, clear, and exact description of the 10 same, and which said drawing constitutes part of this specification and represents a face view.

This invention relates to a design for the 15 handles of spoons, forks, and like articles of table service; and it consists in the configuration and ornamentation of the handle, as shown in the accompanying illustration and hereinafter described.

The shank of the handle is cylindrical for 20 about half its length. At that point it is flattened, gradually expanding toward the end, where it terminates in a segment shape. On the surface is a rose ornament where the first portion intersects the cylindrical part or shank.

Above the rose is a diagonal band composed of parallel beads with ornamentation between. 25 From the rose below a branch springs, apparently passing back of the diagonal band up onto the surface above, the remainder of the handle left plain, and without beading upon the edges, all as shown in the accompanying 30 illustration.

I claim—

The herein-described design for spoon and fork handles, in configuration flat, gradually expanding from about midway of its length, 35 with a rose ornament at the junction of the expanding portion with the shank below, the diagonal band above, and a branch springing from the rose ornament extending on the surface above the diagonal band, the remaining 40 surface of the handle plain, as shown in the accompanying illustration.

FREDERICK WATERHOUSE.
